UNITED STATES PATENT OFFICE.

FRANK E. CASE, OF SCHENECTADY, NEW YORK, ASSIGNOR TO THE
GENERAL ELECTRIC COMPANY, OF NEW YORK.

ELECTRIC BRAKE.

SPECIFICATION forming part of Letters Patent No. 660,487, dated October 23, 1900.

Application filed August 5, 1898. Serial No. 687,821. (No model.)

To all whom it may concern:

Be it known that I, FRANK E. CASE, a citizen of the United States, residing at Schenectady, county of Schenectady, State of New York, 5 have invented certain new and useful Improvements in Electric Brakes, (Case No. 714,) of which the following is a specification.

My invention relates to the art of electric braking and to that class of brakes in which 10 an electromagnet is energized at desired times and by its effect upon a moving part of the machine brings the apparatus to rest. These devices find their most useful application in electrically-operated railways and 15 tramways, in which the electromagnet is usually fixed and of disk-like form, coöperating with a "disk" rotating with the axle.

My invention aims to provide in this class of apparatus a form of support which makes 20 it possible to apply the brake-shoe to the outside of the wheel instead of placing it, as has heretofore been customary, between the wheel and the motor. Many modern forms of electric motor demand the entire axle length on 25 account of the large output now required, and thus no space is left within the wheel-base in which to put the brakes.

In carrying my invention into effect I support the brake-shoe from the truck-frame, 30 preferably mounting it upon the axle-box, and I provide a suitable bearing-surface against which the shoe may rub, either by fac- 35 ing off a portion of the wheel or by applying thereto a properly-machined disk. To avoid variation of the air-gap, and consequent ir- 40 regularity in the braking action, I employ a limiting device of any suitable kind, such that the brake-shoe is compelled to follow the end play of the axle whenever the latter 45 moves to a position which would otherwise increase the air-gap beyond the desired limit. In this way I am enabled to accomplish a result not hitherto obtainable, in that I may employ an integral annular brake-shoe and 50 disk or rubbing-surface with which the brake-shoe coöperates. Heretofore it has been necessary to cut both shoe and disk in order to mount them or else leave a gap through which the axle may pass. In my construc- 55 tion this is not required.

The drawings annexed show an embodiment of my invention.

Figure 1 is a side elevation of a car-wheel and a part of a truck to which the improvement has been applied. Fig. 2 is a partial 55 section upon the line 2 2 of Fig. 1. Fig. 3 is a side elevation, partly in section, upon the line 3 3 of Fig. 2, of the car-wheel and shoe with the axle-box removed. Fig. 4 is a representation of a brake-shoe detached. Fig. 60 5 is a side elevation of the "disk," so called; and Fig. 6 is a section on the line 6 6 of Fig. 4.

A general idea of the arrangement of the mechanism is obtained best from Fig. 2, to which reference will first be made. In de- 65 scribing this figure reference is also had to Figs. 1 and 3, which show other views of the same parts.

A is the tread of the wheel.

B is the web mounted on the axle C. To 70 the web is affixed by the bolts E E the disk D, which thus revolves with the wheel. Also affixed to the web by the screws L L is the collar F, against the inner face of which bears the web H², formed upon the brake-shoe H. 75 The latter is a single casting forming, approximately, an annulus completely closed. In this it differs from all other shoes with which I am acquainted, none of them being an integral structure. The disk D may also, 80 if desired, form a complete annulus. Both these parts may be easily slipped over the journal.

M is the journal-box, mounted in the case 85 illustrated in a pedestal composed of back and front plates n n, held together by bolts N N. Secured to the journal-box in any de- 90 sired manner or made in one with it is a bar G, having a horizontal portion G'. Upon this part of the bar rests the brake-shoe H. At the top and bottom of the shoe are lugs H' H', 95 in suitable bearings in which rest other lugs I I', which prevent the rotation of the shoe when it is energized and applied to the disk or annulus D. The coil Q, constituting the energizing-winding, is mounted in a groove in the body of the shoe and is held in place by a suitable filling. Since the shoe is an integral annulus, I am enabled to make use 100 of an energizing-winding comprising a single

coil, substantially circular in form. In order to prevent the disk from wearing unevenly, I make the groove containing the energizing-winding eccentric to the body of the shoe, as 5 pointed out in the patent to W. G. Cary, No. 539,855, dated May 28, 1895.

As seen in Fig. 1, the bars O of the truck-frame on which the body of the car is supported are carried on the journal-box in the 10 usual way, and springs P are provided wherever it is necessary or desired.

Fig. 4 shows the rubbing-face of the shoe, with the coil shown in dotted lines.

Fig. 5 shows the annulus or disk D, forming the rubbing-surface against which bears the brake-shoe. It is provided with a stiffening-flange d and bolt-holes e e for attaching it to the wheel. The flange d bears against the wheel-center and lessens the strain on 20 these bolts. The disk is, as will be seen, an integral annulus, the utility of which has been already pointed out.

The construction shown in Fig. 6 is sufficiently apparent from the reference-letters, 25 which indicate the same parts as in the other figures.

It will be seen that the mounting of the brake-shoe outside of the wheel-base forms an important feature of my invention and 30 that other features are the devices for limiting the air-gap to a determined maximum and for allowing play of the shoe between limits and the support, more especially, of the shoe in practically invariable relation to 35 the axle, which I find to be conveniently accomplished by placing it upon the axle-box.

What I claim as new, and desire to secure by Letters Patent of the United States, is—

1. In combination in a car-truck, a frame, 40 for supporting the body of the car, provided with bearings for the car-axles, an electric brake-shoe slidably supported from said frame outside of the wheel, and a suitable bearing-surface for said shoe on the outer 45 face of the wheel.

2. In combination in a car-truck, a frame provided with bearings for the car-axles, an electric brake-shoe, comprising an annulus provided with an energizing-winding, slidably supported from said frame outside of the wheel, and a suitable bearing-surface for said shoe on the outer face of the wheel.

3. In combination in a car-truck, a frame provided with bearings for the car-axles, an 55 electric brake-shoe slidably supported from said frame outside of the wheel, and an annulus or disk, provided with a suitable bearing-surface for said shoe, fixed to the axle.

4. In combination in a car-truck, a frame 60 provided with bearings for the car-axles, an electric brake-shoe, means carried by said frame for slidably supporting said brake-shoe between the frame and the wheel, and a suitable bearing-surface on said wheel opposite to said shoe.

5. In combination in a car-truck, a frame

provided with bearings for the car-axles, an electric brake-shoe, means carried by said frame for slidably supporting said brake-shoe between the frame and the wheel, a suitable bearing-surface on said wheel opposite to said shoe, and means carried by the axle for limiting the movement of the shoe away from its bearing-surface.

6. In combination in a car-truck, a frame 75 provided with bearings for the car-axles, an electric brake-shoe supported between the frame and the wheel, a suitable bearing-surface on said wheel opposite to the shoe, and one or more lugs on the frame engaging said shoe to prevent rotation of the same.

7. In combination in a car-truck, a frame provided with bearings for the car-axles, an electric brake-shoe, comprising an annulus 85 provided with an energizing-winding, supported between the frame and the wheel, a suitable bearing-surface on said wheel opposite to said shoe, and one or more lugs on the frame engaging said shoe to prevent rotation of the same.

8. In combination in a car-truck, a frame, boxes for the axle-bearings mounted in said frame, an electric brake-shoe, provided with an energizing-winding, carried by the box between the frame and the wheel, and a suitable bearing-surface for said shoe on the 90 outer face of the wheel.

9. In combination, in a car-truck, a frame provided with bearings for the car-axles, an electric brake-shoe, comprising an annulus 100 provided with an energizing-winding, supported between the frame and wheel, a suitable bearing-surface on said wheel opposite to said shoe, means for preventing rotation of the brake-shoe, and means carried by the 105 axle for limiting the movement of said shoe away from its bearing-surface.

10. In combination, in a car-truck, a frame provided with bearings for the car-axles, an electric brake-shoe, comprising an annulus 110 provided with an energizing-winding, supported between the frame and wheel, a suitable bearing-surface on said wheel opposite to said shoe, means for preventing rotation of the brake-shoe, and a flanged ring carried 115 by the axle, arranged to engage the brake-shoe upon excessive end play of said axle thereby limiting the air-gap between the said shoe and its bearing-surface to a determined maximum.

11. In combination, in a car-truck, a frame provided with bearings for the car-axles, an electric brake-shoe, comprising an annulus provided with an energizing-winding, supported between the frame and wheel, a suitable bearing-surface on said wheel opposite to said shoe, means for preventing rotation of the brake-shoe, and an adjustable device 125 for limiting the movement of said brake-shoe away from its bearing-surface.

12. In combination, in a car-truck, a frame, boxes provided with axle-bearings mounted

in said frame, an electric brake-shoe, comprising an annulus provided with an energizing-winding, between the frame and the wheel, a support for said brake-shoe projecting from said journal-box, and a suitable bearing-surface on said wheel opposite to said shoe.

5 13. A brake-shoe comprising an integral annulus, a groove extending entirely around

said annulus and disposed eccentrically thereto, and an energizing-coil in said groove.

In testimony whereof I have hereunto set my hand this 3d day of August, 1898.

FRANK E. CASE.
